(57) **CLAIM**

The ornamental design for an anal plug, as shown and described.

DESCRIPTION

FIG. 1 is a perspective top view of an anal plug;

FIG. 2 is a bottom plan view of the anal plug of FIG. 1;

FIG. 3 is a top plan view of the anal plug of FIG. 1; and,

FIG. 4 is a side view of the anal plug of FIG. 1.

The broken lines show structure or boundaries that form no part of the claimed design.

1 Claim, 4 Drawing Sheets
